UNITED STATES PATENT OFFICE.

MARIE OPLUSTIL, OF CHICAGO, ILLINOIS.

QUILT-COVER.

1,118,220.

Specification of Letters Patent. Patented Nov. 24, 1914.

Application filed September 17, 1913. Serial No. 790,285.

To all whom it may concern:

Be it known that I, MARIE OPLUSTIL, a subject of the Emperor of Austria-Hungary, and a resident of the city of Chicago, county 5 of Cook, and State of Illinois, have invented certain new and useful Improvements in Quilt-Covers, of which the following is a specification.

My invention relates to improvements in 10 covers for quilts and the like, and has for its object an improved cover of this character which is of simple construction, efficient in operation and ornamental in appearance.

The invention consists in the combinations 15 and arrangements of parts hereinafter described and claimed.

The invention will be best understood by reference to the accompanying drawing forming a part of this specification, and in 20 which,

Figure 1 is a plan view of a cover embodying my invention, partially broken away for the sake of clearness, and Fig. 2, a section taken on line $x-x$ of Fig. 1.

The preferred form of construction as 25 illustrated in the drawing comprises a substantially flat envelop 1 made of ornamental cloth or similar fabric and provided with a substantially rectangular opening 2 in one 30 of the sides thereof. The cover 1 is provided adjacent the corners of opening 2 with four button holes 3 which are positioned to receive buttons 4 secured to the quilt 5. Button holes 3 are preferably formed in a 35 strip 6 of cloth or similar material which is secured to the adjacent portions of the envelop 1 by means of a strip of lace 7 and is provided with a fringe of lace 8 as shown.

In use the quilt is inserted or removed 40 through the rectangular opening 2 of the envelop which thus exposes a portion of the quilt adding to the ornamental effect of the cover. By providing the strip of lace 7 and fringe of lace 8, the flexibility of the 45 construction is increased, a view of the buttons 4 afforded on either side of strip 6 thus facilitating positioning of the envelop, and the

ornamental appearance of the cover is enhanced.

While I have illustrated and described 50 the preferred form of construction for carrying my invention into effect, this is capable of variation and modification without departing from the spirit of the invention. I, therefore, do not wish to be limited to the 55 precise details of construction set forth, but desire to avail myself of such variations and modifications as come within the scope of the appended claims.

Having described my invention what I 60 claim as new and desire to secure by Letters Patent is:

1. The combination with a quilt, of an envelop having an opening in one side; a strip secured to the edges of said opening by 65 open work material, said strip being provided with button holes; and buttons on said quilt engaging said button holes, substantially as described.

2. The combination with a quilt, of a sub- 70 stantially flat rectangular envelop having a substantially rectangular central opening in one side; a strip secured to the edges of said opening by open work material, said strip being provided with button holes; and but- 75 tons on said quilt engaging said button holes, substantially as described.

3. The combination with a quilt, of a sub- 80 stantially flat rectangular envelop having a substantially rectangular central opening in one side; a strip secured to the edges of said opening by open work material, said strip being provided with button holes; a flange of open work material on the inner edges of said strip; and buttons on said quilt engag- 85 ing said button holes, substantially as described.

In testimony whereof I have signed by name to this specification in the presence of two subscribing witnesses.

MARIE OPLUSTIL.
